UNITED STATES PATENT OFFICE.

HENRY H. DENT, OF FULLERTON, PENNSYLVANIA.

DESIGN FOR A LOCK-CASE.

SPECIFICATION forming part of Design No. 24,311, dated May 14, 1895.

Application filed March 2, 1895. Serial No. 540,368. Term of patent 3½ years.

To all whom it may concern:

Be it known that I, HENRY H. DENT, a citizen of the United States, residing at Fullerton, in the county of Lehigh and State of Pennsylvania, have invented and produced a new and original Design for a Lock-Case, of which the following is a specification, reference being had to the accompanying drawings, forming part hereof, in which—

10 Figure 1 is a front elevational view of a lock-case, illustrating the shape or form of my design. Fig. 2 is a sectional view of the same; and Fig. 3 is an edge view, these three views being deemed necessary in order to fully illustrate my design.

15 The leading feature of my design consists of a lock case, comprising the raised surface ornamentation of leaves merging into a spray or bouquet, the outlines of which when viewed in Fig. 1, will fall within the outline of the lock case, the leaf ornaments radiating from approximately the center of the face of the lock-case at or near the key-hole thereof.

20 Referring to the drawings A, is the face of the case in which is situated a key-hole.

25 B and B', are the outer rims of the lock-case irregular in outline and conforming to the outline of the leaf ornamentation C, radiating from the face A.

30 On the face A, and the rims B and B', of irregular outlines are arranged the ornamentations C, of a conventionalized fern-leaf. These ornamentations radiate from a ribbon knot ornament D, situate near the key-hole.

35 The ornament D, of the face A, is a continuation of the flowing ribbon-like ornamentation E, falling among the leaf ornaments C, on either side of the knot-ornament D. The leaf ornaments C, are arranged in fields radiating from the ornament D, to the corners F, of the face A, and from said ornament D, to the out-

lines G and G', of the rims B and B'. The upper rim B, has its surface ornamented with the three fern-like ornamentations C', two of the leaves forming substantially in outline a wreath H, while the third leaf is represented as thrown across the wreath H. On the surface of the lock-case between the outer outline of the wreath H, and the face A, extends the conventionalized acanthus leaf ornamentation J. The lower rim B', has its surface ornamented with the two fern-like ornamentations C'', represented as intertwined or crossed to form the conventionalized acanthus leaf ornaments J, on the lock case extending from the corners of the face A, to the tips of the leaf ornaments C'', and irregular contour G', of the rim B'. On each side of the ribbon-knot ornament D, the face of the lock-case is ornamented with raised ornaments K. Beside the ornaments K, the surface of the lock case is ornamented with a raised ornament L, forming in outline a continuation of the ornaments K. The face of the ornament L, has artistically displayed 65 the acanthus ornaments J', and the two leaf ornaments C'', represented as crossed and intertwined with the ribbon ornament E. One edge of the face A, is ornamented with the corrugations M, as illustrated in Fig. 3, of the drawings.

What I claim is—

The design for a lock-case, substantially as shown and described.

In testimony whereof I have hereunto set 75 my signature in the presence of two subscribing witnesses.

HENRY H. DENT.
